JIG FIXTURE

Zoltan Haydu, Plainfield, and Arthur E. Sutton, New Market, N. J., assignors, by mesne assignments, to Burroughs Corporation, a corporation of Michigan

Application November 28, 1955, Serial No. 549,250

16 Claims. (Cl. 29—25.19)

This invention relates to a jig fixture and in particular to one for precisely positioning, spacing, and assembling small components of a device requiring critical relationships. The invention is particularly useful in jig fixtures for assembling the electrodes of an electron tube and is therefore hereinafter described as embodied in a fixture for this purpose.

An example of an electron tube which the invention is eminently suitable in producing is one described in "Electronic Design" January 1954, pages 14 and 15, and also described in U. S. Patent No. 2,721,955 issued October 25, 1955. This tube is a beam switching type utilizing the combined effects of a magnetic field, produced by an external cylindrical magnet, and electric fields, produced by its internal electrodes, to form, switch and modulate an electron beam in a number of discrete automatically locked positions. For ten positions, the internal elements of the tube include an elongated indirectly heated cathode, a circular array of ten U-shaped spade electrodes for forming and locking the beam, a circular array of ten L-shaped target electrodes, and ten rod-type switching grids. Attention is invited to the aforementioned publication and patent for a more complete description of the construction of this tube and its uniquely versatile performance capabilities.

In electron tubes of this type, the large number of internal electrodes are generally assembled and supported between a pair of insulating, e. g. mica, discs and permanently enclosed within a sealed glass envelope. The position and spatial relationships of the electrodes are very critical for proper operation of the tube, and the electrode assembly must be rugged enough to maintain the critical relationships during handling and use. In producing these electrode assemblies in the past, the general procedure was to manually insert each electrode individually in its proper position between the supporting mica discs. This was accomplished by inserting the lower tabs of the electrodes individually in their respective punched openings of the lower mica disc, with the tabs biting into, or tightly wedged against, the edges of the opening, and then inserting the upper mica disc through the upper tabs of the electrodes. This procedure was a long and tedious one but was felt to be necessary to assemble all electrodes in their critical position and spacing relationships. Nevertheless, these relationships could still not be completely and uniformly held to the critical degree required, which resulted in a high percentage of rejects. Moreover, in manually inserting the individual electrodes through the mica disc openings, it was frequently necessary to turn or twist the electrodes in their openings to work them in and to secure the required critical relationships. This would result in deforming the edges of the mica openings which weakened their support of the electrodes during handling and use of the tube, thereby producing erratic operation of the tube after relatively short use.

The use of a jig fixture embodying the invention here-

inafter described has not only enabled the production of electrode assemblies minimizing the above deficiencies, but has also decreased, to a fraction, the time heretofore required to produce such assemblies. While the invention is eminently useful in the production of electron tubes, it will be quite apparent that it is susceptible of many other applications for assembling small components of a device requiring critical position and spacing relationships.

10 It is therefore a primary object of this invention to provide a jig fixture which is efficient and accurate in the positioning, spacing, and assembling of small components of a device requiring critical relationships.

15 Another object of the invention is to provide a jig fixture utilizing a vacuum for accurately positioning components of a device as they are being assembled.

20 A further object is to provide a jig fixture for accurately positioning a plurality of small components on a common support and simultaneously anchoring all the components to the support whereby they will be uniformly and firmly secured in their proper positions.

25 Still further objects of the invention are to provide a jig fixture of the foregoing character which is especially useful in assembling the electrodes of an electron tube between a pair of mica discs; which accurately positions the electrodes in their critical relationships and retains them in position during their assembly between the mica discs; which securely anchors the electrodes to the mica discs thereby producing a rugged assembly having a long 30 operating life; and which permits the assembly of such devices efficiently and economically on a mass production basis.

These and still further objects of the invention will be apparent from the following description of a jig fixture embodying the invention for use in producing electrode assemblies for electron tubes. The electron tube illustrated is of the aforementioned beam switching, ten position, type having ten sets of electrodes that must be critically positioned and spaced, and firmly supported 35 between a pair of mica discs.

40 The fixture described is provided with a circular array of ten electrode supporting members, one for each set of electrodes, which members are radially projectable from their normal positions to positions corresponding to 45 the placement of their respective electrodes. These members are formed at their inner extremities with surfaces of special configurations to support their electrodes in the proper position on the mica discs between which they are to be assembled. In the disclosed embodiment for use in connection with the aforementioned electron tube, each member is specially formed to support an L-shaped target and a U-shaped spade in their critical relationships to each other, and an important feature of this invention 50 is the use of a vacuum to retain the electrodes in their proper positions during assembly.

55 The electrodes are supported by these members in two circular arrays over the lower mica disc seated in a holder of the fixture. A plunger, disposed in a cover hinged to the fixture, may be used to support the upper mica disc. Another important aspect of the invention is the feature of forcing the tabs of the electrodes through the openings of the mica disc to uniformly bite, or to be firmly wedged against, the edges of the openings with no other deformation of the edges. This firmly anchors the electrodes to the discs in their proper positions and is accomplished by the plunger arrangement in the cover for forcing the electrode tabs simultaneously and uniformly through the mica disc openings.

60 65 70 The invention will be better understood from the following description of a jig fixture embodying the invention which is especially useful in the production of the

above referred to beam switching tube, it being appreciated that the invention could be used with equal advantage in other applications.

In the drawings:

Fig. 1 is a top plan view, partly in section to show internal structure, of a jig fixture constructed in accordance with the invention for use in assembling electrodes of a beam switching tube between a pair of mica discs;

Fig. 2 is a partial sectional view of the fixture of Fig. 1;

Fig. 3 is an enlarged fragmentary perspective view, partly broken away, illustrating one electrode supporting member, its vacuum means for retaining the electrodes, and the upper and lower mica disc holders of the fixture;

Fig. 4 is a top plan view of one of the electrode supporting members and the electrodes supported thereby;

Fig. 5 is a perspective view of the electrode assembly produced with the aid of the jig fixture; and

Fig. 6 is a top diagrammatic view of the electrode assembly of Fig. 5.

Referring first to Figs. 5 and 6 illustrating the electrode assembly produced with the aid of the jig fixture disclosed, it will be seen that such assembly includes an upper and lower insulating, e. g. mica, disc, 2 and 4 respectively, an elongated indirectly heated cathode 6, and two groups of electrodes, ten in each group, arranged in circular arrays around the cathode. The inner group of ten electrodes are U-shaped spades 8 and function to form and lock the electron beam, while the outer group of ten electrodes are L-shaped targets 10 which receive the beam and produce a useful output in any one of the ten locked positions of the beam. These electrodes are positioned in their critical relationships between the two mica discs and firmly secured thereto with the aid of the jig fixture hereinafter described.

The electrode assembly of this type of beam switching tube includes an additional group of ten rod-type switching grids 12 arranged in a circular array between the spades 8 and the targets 10. These electrodes, however, are not assembled by the fixture disclosed as they can be conveniently inserted, in a subsequent operation, through openings in the mica discs after the foregoing electrode assembly has been produced. For a description of the complete structure of this tube, including its external cylindrical magnet, and the performance capabilities of the tube, reference may be had to the publication and patent referred to above.

The jig fixture incorporating the invention comprises generally a housing 20 and a cover 22 hinged thereto for movement from the open position shown in Fig. 1 to the closed position shown in Fig. 2. Housing 20 contains the elements of the fixture which position the electrodes in their proper spatial relationships during their assembly between the two mica discs, and cover 22 contains the means for forcing the electrodes into the mica discs to firmly secure them in place.

Referring to Fig. 2, the housing 20 comprises a base plate 24 which supports the means for positioning the electrodes, these means being disposed in a plurality of sections 26 arranged in a circular array directed towards the central axis of the fixture. Each of the sections 26 houses an electrode supporting, or chuck, member 28 which positions its respective electrodes. In the fixture disclosed for use in connection with the aforementioned tube, there are ten sections 26 each having a chuck member 28 for supporting two electrodes, i. e. a spade 8 and a target 10.

The sections 26 are formed of metal blocks having their side walls converging towards, but terminating short of, the central axis of the fixture thus defining a circular well 25 in which the chuck members 28 extend from their respective sections. The chuck members are provided at their inner extremities with surfaces of

special configuration and with vacuum means for supporting and retaining in proper position their respective electrodes as will be described below in detail. The sections are individually secured to the base plate by bolts 27.

Means are provided for moving the chuck members 28 from their outward positions, shown in Fig. 2, radially inwardly to their inward positions, shown in Fig. 1, corresponding to the placement of their respective electrodes. For this purpose, each of the sections 26 is provided with a cylindrical passageway, or bore, 29 longitudinally therethrough, and an apertured end cap 30 secured to its outer extremity by fasteners 31. A shaft 32 for each section is disposed within the bore 29 and extends through the aperture of end cap 30. The inner portion of shaft 32 is of larger diameter and is provided at its inner end with a blind opening in which a boss 33 extending from chuck member 28 is seated and retained by stud 34. The outer portion of shaft 32, extending through end cap 30, is of smaller diameter and carries at its outer extremity a collar 36 fastened thereto by threaded stud 38. Collar 36 abutting against the end cap 30, serves as a forward stop to limit the forward, or inward, movement of shaft 32 and its chuck member 28, and for that purpose it may be accurately positioned by its threaded stud 38.

To limit the return movement of chuck members 28, each of the shafts 32 is provided with a sleeve 40 press-fitted thereon and a bushing 42 pinned thereto. Sleeve 40 abutting against end cap 30 and retained by bushing 42 serves as a return stop for chuck member 28.

In the fixture disclosed, pneumatic means are used to project and return the chuck members 28. For this purpose, bushing 42 and end cap 30 are provided with sealing rings 44 and 46, respectively, for sealing the expandable chamber 43 defined by these elements within the passage 29. Channels 48 formed in the end cap 30 communicate at one end with expandable chamber 43 and at the other end with an air hose connector 49 connectable to an air supply for all the sections, not shown. It will thus be seen that as air is forced into the expandable chambers 43, the shafts 32 and their chuck members 28 will be projected inwardly until their collars 36 limit on end caps 30 (as shown in Fig. 1); and as the air is exhausted, these members will be returned to the position of Fig. 2 wherein sleeves 40 contact end caps 30.

The larger diameter portion of shafts 32 are flattened at 32', and metal inserts 50, secured to sections 26 by fasteners 51, are provided with depending flanges 52 in contact with the flattened surfaces 32'. This arrangement constrains shafts 32 from any rotary movement and also vents to the atmosphere the air trapped in passage 29. A cylindrical plastic sleeve 54 in each of the passages 29 separates shafts 32 from the inner surfaces of sections 26.

Housing 20 is also provided with means for holding the lower mica disc 4 in position during its assembly with electrodes 8 and 10. A cylindrical tube 60, closed at one end, is secured at its open end to an opening in the base plate 24, by fasteners 62, along the central axis of the fixture and directly below the circular well 25 defined by sections 26. Tube 60 carries a shaft 64, at one end of which is secured a mica holder 66 having a depending boss 68 retained in a blind opening of the shaft by stud 70. A plastic sleeve 71 is interposed between shaft 64 and tube 60, and extends through the opening in base plate 24 to be flush with its top surface.

The foregoing structure supports the lower mica disc 4 during its assembly, and also supports the electrode assembly after it is completed in a manner later described. To facilitate the removal of the complete assembly from the fixture, either manually or automatically, it is desirable to raise mica holder 66 out of the

circular well. For this purpose, a dished disc 72 is secured to the lower end of shaft 64 by a fastener 74, and the closed end of tube 60 is provided with an air channel 76 communicating with the air source (not shown) by connector 78 controlled by air valve 80. Thus, mica holder 66 is projectable out of the circular well by pneumatic means. As air is forced into channel 76, shaft 64 and mica holder 66 are raised until disc 72 contacts sleeve 71, and as the air is exhausted, the elements are returned to the position shown in Fig. 2 with the disc 72 resting against the closed end of tube 60. Shaft 64 is provided with a longitudinal groove 64' in which is seated stud 82 passing through tube 60 and sleeve 71. This prevents any rotary movement of the shaft and also vents the air that may be trapped within tube 60 above disc 72.

The lower mica disc holder 66 is shown in detail in Fig. 3. A thickened rim 90 thereof circumscribes the surface of the holder adapted to contain the mica disc 4, the latter having projections, or tabs, 92 snugly engaging the rim. The holder 66 is further provided with an inner circular trough 94 to accommodate the tabs of the spade electrodes 8 and an outer circular trough 96 to accommodate the tabs of the target electrodes 10. The disc holder 66 is further provided with three projecting pins 98 adapted to pass through corresponding punched apertures in mica disc 4. These pins are so spaced to assure that the disc 4 will be properly positioned in the holder with the upper surface facing up and with its punched openings in registration with the electrode tabs. A counter-bored opening 97 is further formed in the holder 66 in which an elongated pin 99 is disposed. The pin passes through a central punched aperture in the mica disc 4, when the latter is placed thereon, and support the elongated tubular cathode 6.

As shown in Fig. 3, the punched openings 5 in the mica disc 4 receiving the tabs of electrodes 8 and 10 are triangular in form, and have one side thereof 5' of the same dimension as, or preferably slightly smaller than, the width of its corresponding electrode tab. Accordingly, when the electrode tabs are forced through the openings in the mica discs, in the operation later to be described, they will bite into, or be firmly wedged against, the edges bordering the ends of sides 5' of the openings 5, thereby securely anchoring the electrodes to the discs.

As mentioned earlier, housing 26 has associated therewith a cover 22 containing the means for forcing the upper and lower mica discs into secure engagement with the electrodes. Referring to Fig. 2, cover 22 comprises a sleeve 100 having an enlarged annular flange 102 at the lower end thereof pivotally mounted to the housing 26 by means of a hinge 104 and bolts 105 and 106. An upper mica disc holder 108 is supported within sleeve 100 by means of a shaft 110 having a blind opening at its lower end in which a boss 112 of the holder 108 is secured by stud 114. Shaft 110 extends through sleeve 100, separated by plastic liner 115, and is pinned at its upper end to a plunger knob 116 which can be manually depressed to force shaft 110 and its holder 108 downwardly. Thus, it will be apparent that when the electrodes and the mica discs have been properly positioned in the circular well 25 of the fixture, depression of knob 116 will force the electrode tabs simultaneously and uniformly through the mica disc openings.

The lower limit of the plunger movement is determined by the lower end of knob 116 abutting against the upper end of sleeve 100, and it will be obvious that knob 116 could be made adjustable on shaft 110 to vary this limit. To limit the upper movement of the plunger, the diameter of sleeve 100 is reduced, defining a shoulder 117, and shaft 110 carries a bushing 118 to limit thereon. Shaft 110 is also formed with a longitudinal groove 110' adapted to have seated therein a stud 120 passing through

sleeve 100 and liner 115, to prevent rotary movement of the shaft as it is depressed by plunger knob 116.

Referring to Fig. 3, it will be seen that the upper mica disc holder 108 is constructed substantially the same as the lower holder 66, it being formed with a thickened rim 120, inner and outer circular troughs 124 and 126, respectively, and registration pins 128. A pin corresponding to elongated pin 99 of the lower holder is omitted from the upper holder as the tubular cathode 6 is supported by the lower holder.

Each of the chuck members 28 is formed with surfaces of special configurations to support its pair of electrodes in their proper positions, and each is further provided with vacuum means to retain them so positioned during assembly. These are important features of this fixture, as the two electrodes of each chuck member 28 must be exactly placed in their critical positional and spatial relations with respect to each other and with respect to the electrodes of the other chuck members, and firmly anchored between the mica discs in these critical relationships. Figs. 3 and 4 illustrate the structure of a chuck member 28 for accomplishing this.

The chuck members 28 are each formed with a pair of electrode supporting surfaces for supporting an L-shaped target 10 and a U-shaped spade 8 (Figs. 3 and 4). The former supporting surface is formed in sidewall 130 of the chuck member by a notch, or cut-out, defined by walls 131 and 132. Wall 131 is about the same width as its corresponding side 10' of the target electrode, and forms the same angle with wall 132 as does side 10' of the electrode with its other side 10''. In the embodiment disclosed, the former dimension is 0.144" and the latter angle is 80°. Wall 132, however, extending to the end tip of the chuck member is substantially wider than its corresponding side 10'' of the target electrode. In this embodiment, side 10'' is 0.117" wide, whereas wall 132 to the tip of the chuck member would be about 0.200". Wall 132 merges with curved tip 133, having a short flattened portion 134, and then joins with the other side wall 135 of the chuck member thus defining the surface for supporting the U-shaped electrode 8. The two straight sides 8' of the U-shaped spade are 0.016" wide, in the embodiment disclosed, and merge with the bight, or looped, portion 8'' having an internal radius of curvature of 0.021", forming an angle of about 38° between the two sides. The curved tip 133 of the chuck member, accordingly, also has a radius of curvature of 0.021", and extends for substantially more than half the arc of loop 8''. The flattened portion 134 of the curved tip 133, contiguous to side wall 135, is adapted to engage the portion of the straight side 8' merging with loop 8'' of the electrode and thus stabilize the support of the electrode in its proper position. In this position, as is apparent from the drawings, one side 8' of electrode 8 is supported in an overlapping, but spaced, relation to one side 10'' of the other electrode 10.

To provide the vacuum means for retaining the electrodes in their proper positions on the chuck members, each of the latter is formed with an internal bore 136 connectable to a vacuum source (not shown) through a conduit 137 passing through an elongated opening in the base plate 24. Three spaced air channels 138 are drilled through wall 131 adjacent its inner extremity, and three further spaced air channels 139 are drilled through the curved tip 133, both sets of air channels extending to the internal bore 136. Thus, with the internal bore 136 connected to a vacuum source, the vacuum produced through channels 138 and 139 will retain electrodes 8 and 10 in their proper positions on the chuck members during their assembly with the mica discs.

A typical operation, described below, illustrates the use of this fixture in assembling the electrodes between the mica discs. At the start of a typical assembly operation, the cover 22 of the fixture would be open as shown in Fig. 1, and the chuck members 28 would be in their with-

drawn positions as shown in Fig. 2. Also, the lower mica disc holder 66 could be in its upper position. In the following sequence, the operator then performs the following steps: Inserts a mica disc 4 in the lower holder 66 in proper registration with the pins 98 thereof, and a tubular cathode 6 over the elongated pin 99 of the holder (see Fig. 3); by the pneumatic controls, lowers holder 66, projects the chuck members 28 into the circular well 25 above the holder, and turns on the vacuum means for the chuck members; manually inserts the ten target electrodes 10 in the notched portions of the chuck members and the ten spade electrodes 8 against the curved tips of the chuck members; with one hand, inserts a mica disc 2 in the upper holder 103 in proper registration with its pins 128 slightly pushing it up within its sleeve 100, and with the other hand pivots the cover 22 closed over the circular well; manually depresses knob 116 to its limit thus forcing all the electrodes simultaneously and uniformly through their respective openings in the mica discs; by the pneumatic controls, withdraws the chuck members 28 and turns off the vacuum source; pivots the cover 22 open and pneumatically raises lower holder 66 out of the circular well; and removes the electrode assembly from holder 66. The fixture is then in condition for the next assembly operation.

While the above typical operation taken for illustrative purposes was a simple manual one, it will be apparent that this fixture is susceptible of varying degrees of automatic operation by the utilization of automatic loading and ejecting devices, and the provision of automatic controls. Also, the invention could be advantageously embodied in fixtures for assembling devices other than electrode assemblies. Many other applications and modifications will be apparent to those skilled in the art also coming within the spirit and scope of the invention as defined in the following claims.

We claim:

1. A jig fixture for positioning and assembling small components of a device to a common support comprising; holder means for the common support, a plurality of members radially projectable over said holder means to positions corresponding to the placement of the components on the common support, said members being adapted to support the components to be assembled in their proper positions, means overlying said members in their projected positions and adapted to force simultaneously all said components into secure engagement with the common support, and means for radially withdrawing said members from over said holder means to facilitate the removal of the assembled components and support.

2. A jig fixture for positioning and assembling electrodes between a lower and upper insulating disc comprising; a holder for the lower insulating disc, a plurality of members arranged in a circular array for supporting the electrodes to be assembled in their proper positions, means for radially projecting said members over said holder to the positions corresponding to the placement of the electrodes on the lower insulating disc, vacuum means associated with said members for retaining the electrodes in their proper positions, a holder for the upper insulating disc overlying said members in their projected positions, means for forcing all the electrodes simultaneously into secure engagement with both insulating discs, and means for radially withdrawing said members from over said holder to facilitate the removal of the assembled electrodes and insulating discs.

3. A jig fixture for use in positioning and assembling electrodes to an insulating disc comprising; a holder for the insulating disc, a member being formed with a curved tip at one end thereof for supporting one electrode and with a notched wall adjacent said end for supporting another electrode, vacuum means communicating with said curved tip and notched wall, and means for projecting said member with respect to said holder to the posi-

tion corresponding to the placement of the electrodes on the insulating disc.

4. A jig fixture for use in positioning and assembling electrodes to an insulating disc comprising; a holder for the insulating disc, a member for supporting said electrodes with respect to said holder in positions corresponding to their placement on the insulating disc, said member being formed with a curved tip at an end thereof proximate to said holder and with a notched wall adjacent said end, vacuum means communicating with said curved tip and notched wall, and means for forcing simultaneously the electrodes supported by the member into engagement with the insulating disc.

5. A jig fixture for use in positioning and assembling electrodes to an insulating disc comprising; a holder for the insulating disc, a member for supporting the electrodes, said member being formed with a curved tip at one end thereof and with a notched wall adjacent said end, vacuum means communicating with said curved tip and notched wall, means for projecting said member with respect to said holder to the position corresponding to the placement of the electrodes on the insulating disc, and plunger means for forcing said electrodes into secure engagement with the insulating disc.

6. A jig fixture for use in positioning and assembling electrodes to an insulating disc comprising; a holder for the insulating disc, a plurality of members, each for supporting a pair of electrodes, arranged in a circular array about said holder, each of said members being formed with a curved tip at one end thereof for supporting a first electrode and with a notched wall adjacent said end for supporting another electrode in overlapping spaced relation with respect to the first, vacuum means communicating with said curved tip and notched wall of each member, and means for projecting said members over said holder to the positions corresponding to the placement of the electrodes on the insulating disc.

7. A jig fixture as defined in claim 6 including plunger means overlying said members in their projected positions and adapted to force simultaneously all the electrodes into secure engagement with the insulating disc.

8. A jig fixture as defined in claim 7 including means for raising said holder for the insulating disc.

9. A jig fixture for positioning and assembling electrodes between a lower and upper insulating disc comprising; a housing having a plurality of sections arranged in a circular array, each of said sections having their side walls converging towards, but terminating short of, the center axis of the fixture thus defining a circular well, a holder for the lower insulating disc disposed below the circular well, a plurality of members extending through said sections into the circular well for supporting the electrodes to be assembled in their proper positions, means for projecting said members over said holder to the positions corresponding to the placement of the electrodes on the lower insulating disc, and plunger means including a holder for the upper insulating disc overlying said first-mentioned holder and said members in their projected positions and adapted to force simultaneously all said electrodes into secure engagement with the lower and upper insulating discs.

10. A jig fixture as defined in claim 9 including means at the center of said first-mentioned holder for supporting a tubular cathode.

11. A jig fixture as defined in claim 9 wherein the supporting members are each formed with a curved tip at the end projecting into the circular well and with a notched wall adjacent said end, and wherein each supporting member includes vacuum means communicating with said curved tip and notched wall.

12. A jig fixture as defined in claim 11 including means for raising the holder for the lower insulating disc.

13. A jig fixture as defined in claim 12 wherein the plunger means and the holder for the upper insulating disc are disposed in a cover hinged to said housing.

14. A jig fixture for use in assembling small components of a device between a pair of supports comprising; a holder for each of said supports, a plurality of separate members arranged in a circular array about one of said holders and radially projectable thereover, each of said members being configured to position a plurality of components in mutually spaced relationship and in positions with respect to said holders corresponding to their placement between the pair of supports, means cooperating with one of said holders for simultaneously forcing all the components into secure engagement with the pair of supports, and means for radially withdrawing said members from over said holder to facilitate the removal of the assembled components and supports.

15. A jig fixture for use in assembling electrodes between a pair of insulating discs comprising; a holder for each of said insulating discs, a plurality of separate members arranged in a circular array about one of said holders and radially projectable thereover, each of said members being configured to position at least a pair of electrodes in mutually spaced relationship and in positions with respect to said holders corresponding to their placement between the pair of insulating discs, means cooperating

with one of said holders for simultaneously forcing all the electrodes positioned by said members into secure engagement with the pair of insulating discs, and means for radially withdrawing said members from over said holder to facilitate the removal of the assembled electrodes and insulating discs.

16. A jig fixture for use in assembling electrodes between a pair of insulating discs comprising; a holder for each of said insulating discs, a plurality of members arranged in a circular array about one of said holders, each of said members being formed with a curved tip at one end thereof for supporting a first electrode and with a notched wall adjacent said end for supporting another electrode in overlapping spaced relation with respect to the first, and means for simultaneously forcing all the electrodes positioned by said members into secure engagement with the pair of insulating discs.
